UNITED STATES PATENT OFFICE.

MAX A. SKALL, OF NEW YORK, N. Y.

DISPLAY-FIXTURE.

1,280,883.

Specification of Letters Patent.

Patented Oct. 8, 1918.

Application filed February 11, 1918. Serial No. 216,656.

To all whom it may concern:

Be it known that I, MAX A. SKALL, a citizen of the United States, and residing at New York city, in the county and State of 5 New York, have invented certain new and useful Improvements in Display-Fixtures, of which the following is a specification.

This invention relates to certain improvements in the construction of display stands 10 or cases and particularly to that class of such cases which are portable and conveniently placed on the sales counters in stores for the display of special merchandise and which also provide convenient means to advertise 15 the merchandise which they contain and enable the customer to select a particular kind of the goods displayed.

The objects of my improvement are to provide a combined display cabinet and 20 stand for "sanitary" packed goods which are sold in boxes of which an assortment is stored in the case and a sample displayed thereon. A further object is to provide means for the customer to select one of the 25 boxes from the assortment and remove it from the case in an easy manner.

With these and other objects in view the invention consists in certain novel details of construction and arrangements of parts 30 hereinafter described and shown and illustrated in the accompanying drawings, made part of these specifications in which—

Figure I is a front elevation of my display stand and case.

Fig. II is a side elevation of the same stand.

Fig. III is a plan view of Fig. I.

Fig. IV is a side elevation in large scale of the display stand on top of the case.

Fig. V is a plan view of Fig. IV.

Similar characters of reference indicate corresponding parts throughout the various views.

My display fixture is preferably constructed as follows: The base plate 1, sides 2 and 3 front plates 4 and 4^a and top plate 5 consist of frames or sections separately made from U shaped metal channels 6 in which panels 7 of suitable material as metal 50 or paper covered paste board, wood or glass are mounted. Front plate 4 is preferably provided with a diamond shaped opening 8 whose edges are framed by metal channels. The side plates 2 and 3 as well as plate 4^a 55 are conveniently provided with advertising

matter relating to the goods displayed. The boxes 9 containing the goods to be vended, are stacked one above the other in the interior of the case in such a manner, that their labels indicating grade or color 60 of the goods contained in each individual box, are displayed through opening 8 of plate 4. Each of the side plates 2 and 3 carry at their rear upper ends a short vertical tubular sleeve 10 into which a bent rod 11 is inserted, the horizontal part 11^a of this rod carrying a mirror 12 whose frame 13 is preferably soldered to rod 11^a. Top plate 5 is also provided at its rear upper end with two short horizontal tubular sleeves 15 65 which accommodate the ends of a shaped wire frame 14 forming a hinge for the same. This wire is shaped in such a manner that it forms two loops 14^a at its extreme front ends joined by a horizontal part 14^b between 70 them. This frame when swung on its hinges into the position shown on the drawings supports one of the boxes, 9, opened and in slanted position, to display the goods contained therein; the loops 14^a press slightly 75 against the side walls 9^a of the box clamping the same while the lower front edge 9^b rests against the channel 6 of the frame of top plate 5 and the bottom 9^c of the box leans against the horizontal bar 14^b of the 80 frame.

The use and operation of this display fixture offer many advantages. A customer may select the kind or color of the goods displayed, through the opening in the front 90 face and push the particular box of his selection out through the open rear of the case, with his finger as indicated in Fig. II. For neckties or similar furnishings the mirror 12 forms a welcome adjunct for trying on. 95 The display of the goods is facilitated by the adjustability of the box 9, on top of the case to any angle with the horizontal plane and the easy manner in which the box may be securely erected and clamped by loops 100 14^a. A further advantage is to be found in the fact that the case and stand may be brought to a rectangular shape in any direction, by removing the mirror 12 and frame 11 from the holding sleeves 10 and by removing the display box 9, which lets the frame 14 rest flat against top plate 5 of the case. The mirror with frame 11 may then be stored in the interior of the case for packing and shipping.

Having thus described my invention what I claim as new and desire to secure by Letters Patent is:

1. In a display fixture of the kind described, a casing adapted to inclose a stack of containers in parallel alinement on vertical sides, an aperture near the center of the front side of said casing, adapted to display a plurality of superimposed containers and providing means for extrusion of a selected container from its position between adjacent containers, perpendicularly to said front side and through the open rear side of said casing.
2. In a display fixture of the kind described, a casing adapted to inclose a stack of containers in parallel alinement an aperture in the center of the front side of said casing; adapted to display a plurality of containers and providing means for extrusion of one of said containers from its position between adjacent containers through the rear side of said casing; a wire frame to support one of said containers above said casing, means on said casing for pivotal attachment of said frame and independent clamping means on said frame to hold said container.
3. In a display fixture of the kind described, a casing adapted to inclose a stack of containers in parallel alinement an opening in the front side of said casing to display a plurality of containers for selection and providing means to extrude one of said containers from its position between adjacent containers through the open rear side of said casing, hinges on said casing holding a wire frame by the ends of its wire and independent means on said frame to clamp one of said containers to said frame and vary its slanted position on said casing.
4. In a device of the kind described, a casing, a box supported on said casing in variable slanted position, tubular members attached to said casing, a wire frame rotatably mounted in said tubular members by the ends of said wire and friction means formed by intermediate parts of said wire to rotatably clamp said box to said frame and to vary the inclination of said box on said casing.
5. In a device of the kind described a casing a box supported in variable slanted position on said casing a wire frame rotatably attached to said casing, bent to provide a horizontal bar for the support of the back of said box and a pair of loops at the ends of said horizontal bar forming frictional means to engage the sides of said box and to permit a sliding and angular adjustment of said box on said casing.
6. In a display fixture of the kind described a casing adapted to exhibit a plurality of boxes and providing means for extrusion of one of said boxes from its position between adjacent ones, and one of said boxes being removably joined to the top plate of said casing, a substantially rectangular frame formed by a continuous wire, hinged to said casing and provided with loops bent in the plane of said frame at its free corners, said loops being adapted to rotatably and slidably clamp said box to said frame to permit angular adjustment of said box in clamped position on said casing.

MAX A. SKALL.
